UNITED STATES PATENT OFFICE.

SILAS P. WRIGHT, OF LOS ANGELES, CALIFORNIA.

LUNCH-COUNTER RACK.

Application filed January 28, 1924. Serial No. 689,176.

To all whom it may concern:

Be it known that I, SILAS P. WRIGHT, a citizen of the United States, residing at Los Angeles, in the county of Los Angeles and State of California, have invented certain new and useful Improvements in Lunch-Counter Racks, of which the following is a specification.

The present invention relates to a lunch counter rack for holding sugar bowls, pepper and salt shakers, sauce bottles, napkins, and a bill of fare. The principal object of the invention is to provide a device of this nature which may be attached to the ordinary lunch counter so that it may be moved to an out-of-the-way position when it is desired to clean the counter.

Another important object of the invention is to provide a device of this nature having a simple and efficient construction, one which is reliable, inexpensive to manufacture, attractive in appearance, and well adapted to the purpose for which it is designed.

A still further object of the invention is to provide a device of this nature having a compact structure the parts of which are easily assembled and attached to the lunch counter by any one, no extraordinary mechanical skill being required.

With the above and numerous other objects in view as will appear as the description proceeds, the invention resides in certain novel features of construction, and in the combination and arrangement of parts as will be hereinafter more fully described and claimed.

In the drawing:

Figure 1 is a perspective view of the device embodying my invention showing the same associated with a lunch counter;

Figure 2 is a fragmentary side elevation thereof;

Figure 3 is a detail section taken substantially on the line 3—3 of Figure 1; and

Figure 4 is a detail view showing one of the standards with a portion of the rail associated therewith.

Referring to the drawing in detail it will be seen that 1 designates an ordinary lunch counter to which my device is to be attached. A pair of standards 2 are attached to the edge of the counter 1 by means of screws 3 or similar devices and the upper end of these standards are bent over so as to form

sleeves 4. A rail 5 is of substantial U-shape in formation having offset terminals in the form of legs 6. The intermediate portion of the rail 5 is provided with a pair of reduced rounded portions 7 adapted to be received and journaled in the sleeves 4. Such articles as sugar bowls, pepper and salt shakers, and sauce bottles may be placed on the counter within the confines of the rail 5. A bar 8 is attached to the inner side of the intermediate portion of the rail 5 so as to be spaced therefrom, washers 9 being utilized for this purpose. A container indicated generally at 10 is attached to the bar 8 so as to normally rest upon the counter 1. The space between the bar 8 and the intermediate portion of the rail 5 may be utilized for holding a bill of fare or menu card and the length of this bar 8 may be varied to accommodate the width of said card.

The container 10 is formed of a plurality of U-shaped members 12 and 13. The intermediate portions of the U-shaped member 12 extend longitudinally while the intermediate portions of the U-shaped member 13 are disposed transversely thereof and fixed thereto by means of bolts or in any other suitable manner. The legs of the U-shaped members 12 and 13 extend vertically and are fixed to a substantially rectangular shaped bail 14 at their upper terminals. This container is utilized for holding napkins or the like.

When it is desired to clean the counter 1 it will be seen that the rail 5 may be fulcrumed so that it and the container 10 may be moved from off the counter thereby being in an out-of-the-way position so that the various articles may be removed from the counter and the same thoroughly cleaned. The embodiment of the invention which I have disclosed in detail merely illustrates the preferred example of the device and it is evident that numerous changes in the details of construction, and in the combination and arrangement of parts may be resorted to without departing from the spirit or scope of the invention as hereinafter claimed or sacrificing any of its advantages.

What is claimed is:

1. In an attachment for a counter, a pair of standards adapted to rise from the counter, a rail of U-shaped formation terminating at its ends in offset legs adapted to rest on the counter, the intermediate por-

tion of said rail being journaled in said standards, a bar fixed in spaced relation to the intermediate portion of the rail, and a container attached to said bar and adapted 5 to normally rest on the counter.

2. In an attachment for a counter, a pair of standards adapted to rise from the counter, a rail of U-shaped formation terminating at its ends in offset legs adapted 10 to rest on the counter, the intermediate portion of said rail being journaled in said standards, a bar fixed in spaced relation to the intermediate portion of the rail, and an article carrier attached to said bar.
- 15 3. In an attachment for a counter, a pair of standards adapted to rise from the counter, a rail of U-shaped formation terminating at its ends in offset legs adapted to rest on the counter, the intermediate portion 20 of said rail being journaled in said

standards, a bar fixed in spaced relation to the intermediate portion of the rail, and an article carrier attached to said bar, bolts securing the ends of the bar to the intermediate portion of the rail, and spacing elements upon the bolts between the ends of the bar and the rail. 25

4. In an attachment for a counter, a rail of substantially U-shape in formation and having offset extensions forming legs adapted 30 to rest on the counter, the intermediate portions of the rail having spaced reduced portions of rounded form, a pair of standards adapted to be fixed to the counter and having bearings at their upper ends engaging the reduced rounded portions of the rail, and an article holder carried by the rail. 35

In testimony whereof I affix my signature.

SILAS P. WRIGHT.
